CABINET FOR ELECTRONIC EQUIPMENT AND THE LIKE

Bernie B. Berry, Jr., Indianapolis, Ind., assignor to Vent-
Rak, Inc., Indianapolis, Ind., a corporation of Indiana

Filed Apr. 24, 1962, Ser. No. 69,830

Term of patent 14 years

(Cl. D26—5)

FIG. - 1

FIG. - 2

FIG. 3

FIG. 4

FIG. 5

FIG. 1 is a perspective view of a cabinet for electronic equipment embodying the ornamental design;

FIG. 2 is a side elevational view on a smaller scale;

FIG. 3 is a rear elevational view;

FIG. 4 is a view in top plan on a reduced scale; and

FIG. 5 is an end elevational view of one of the identical drawer pulls.

The side of the cabinet not shown is substantially the same as the side shown.

I claim:

The ornamental design for a cabinet for electronic equipment, as shown and described.
